United States Patent Office

Des. 195,796
Patented July 30, 1963

195,796

INFLATABLE FLAG FOR DIVERS OR SIMILAR ARTICLE

James S. Christiansen, Long Beach, Calif., assignor to Healthways, Los Angeles, Calif., a corporation of California

Filed May 7, 1962, Ser. No. 69,996

Term of patent 14 years

(Cl. D71—1)

FIGURE 1 is a front elevational view of an inflatable flag for divers or similar article showing my new design; FIGS. 2 and 3 are side elevational views thereof; and FIG. 4 is a top plan view thereof.

I claim:

The ornamental design for an inflatable flag for divers or similar article, substantially as shown.
